JOHN R. CAUTLEY AND FREDERICK C. FRANK, OF SOUTH BEND, INDIANA, ASSIGNEES
TO BENDIX BRAKE COMPANY, OF SOUTH BEND, INDIANA, A CORPORATION OF
ILLINOIS

BRAKE

Application filed October 15, 1930. Serial No. 488,768.

This invention relates to brakes, and is illustrated as embodied in internal expanding self-energizing brake for an airplane. An object of the invention is to strengthen 5 the backing plate or its equivalent, to take braking torque and the like, by a novel built-up construction which facilitates the use of aluminum alloy stampings, thus minimizing the weight. Various features relate to reinforcing 10 the plate at the anchorage, also at the camshaft bearing or its equivalent, and to providing an outboard support for the end of the brake anchor opposite the backing plate, and to other novel and desirable structures 15 which will be apparent from the following description of the illustrative embodiments shown in the accompanying drawings, in which:

Figure 1 is a vertical section through the 20 brake, just inside the head of the brake drum, showing the brake shoes in side elevation;

Figure 2 is a partial radial section, on the line 2-2 of Figure 1, showing the camshaft 25 mounting;

Figure 3 is a partial section, on the line 3-3 of Figure 1, showing one of the posts supporting an outboard member for the anchor;

Figure 4 is a partial chordal section, on the 30 line 4-4 of Figure 1, showing the floating joint between the shoes;

Figure 5 is a partial chordal section, on the line 5-5 of Figure 1, showing the mounting 35 of the camshaft and of the anchorage;

Figure 6 is a section corresponding to Figure 1, but showing a somewhat different construction;

Figure 7 is a section through the brake of 40 Figure 6, on the line 7-7 of Figure 6; and

Figure 8 is a partial chordal section on the line 8-8 of Figure 6, showing the mounting 45 of the camshaft and of the anchor.

The brake of Figure 1 includes a rotatable 50 drum 10, at the open side of which is a backing plate 12, and within which is the friction means, illustrated as of the self-energizing type including primary and secondary shoes 14 and 16. Shoe 16 is anchored at one end and at the other end has riveted thereto spaced projecting arms 18 between which the lower

end of shoe 14 is pivoted on a pivot 20 having riveted at its end a forked stop 22 embracing an eccentric stop 24 carried by the backing plate. The brake is applied by means such as a pair of cams 26 engaging rollers 28 on the 55 end of shoe 14, and mounted on a shaft 30 operated by a lever 32. The cams apply the brake against the resistance of a main return spring 34 and an auxiliary return spring 36.

The present invention relates primarily to 60 the reinforcement of plate 12 or its equivalent, by building it up with steel or aluminum alloy stampings, so that aluminum alloy may be used for the plate itself. Thus in Figures 1-5, an annular reinforcing stamping 40, 65 having a central axle opening registering with the central opening of the backing plate, is welded (or riveted) to the backing plate about said opening, and has a lateral extension projecting upwardly and also secured to the plate preferably with one or more spacers 42 embraced between it and the plate.

Stamping 40 and plate 12 are additionally secured together by a bushing 44 serving as 70 a bearing for the camshaft 30 and which is formed with portions riveted over against the stamping and the plate respectively. Stamping 40 is also held by three posts 46, 48, and 50, the first of which is secured to plate 12 by a nut 52 and the other two of which are riveted over as shown in Figure 3. Post 46 serves as the brake anchor, and the upper end of shoe 16 is pivoted thereon as shown in Figure 5. Posts 46, 48, and 50 carry 75 an outboard member such as a triangular flat plate 54, thereby distributing the braking torque over a large area of the backing plate. Post 50 passes through a relatively large 80 clearance opening 56 in shoe 16.

In the arrangement of Figures 6-8, there 85 is an annular reinforcing stamping 140 corresponding to stamping 40, and embracing between itself and the backing plate spacers 142. These are additionally held also by the camshaft bearing or bushing 144. In this 90 case, however, the outboard member for anchor 146 is a stamping or equivalent part 154 riveted or otherwise secured to, and projecting radially outward from, another annular 95 reinforcing stamping 150 riveted to the back- 100

ing plate about its central opening. Anchor 146 may have an eccentric bushing 160 to facilitate adjustment.

The anchor bolt 146 in the arrangement shown passes through the following parts in order: (1) the backing plate 12, (2) spacers 142, (3) the reinforcing stamping 140, (4) the shouldered eccentric bushing 160 on which the shoe is pivoted and whose head engages stamping 140, and (5) a second bushing 162 riveted to the outboard part 154 and engaging the outer end of the first bushing 160. All these parts are clamped tightly together by a nut 152 on the anchor bolt 146, thereby distributing the braking torque over almost the entire backing plate.

While two illustrative embodiments have been described in detail, it is not our intention to limit the scope of the invention to those particular embodiments, or otherwise than by the terms of the appended claims.

We claim:

1. A brake assembly comprising a backing plate having a central axle opening, an annular stamping secured to the plate about said opening and having a part projecting radially outward paralleling said plate and spaced therefrom, and friction means having an anchor supported at one end by the plate and at the other end by said part.

2. A brake assembly comprising a backing plate having a central axle opening, an annular stamping secured to the plate about said opening, a second stamping secured to the annular stamping and projecting radially outward paralleling said plate and spaced therefrom, and friction means having an anchor supported at one end by the plate and at the other end by said second stamping.

40 3. A brake backing plate having a central reinforcing stamping with a part opposite the outer portion of the plate and with an anchor supported at opposite ends respectively by the plate and said part.

45 4. A brake backing plate having at its center an annular reinforcing stamping provided with a second and outwardly-projecting stamping with its end arranged opposite the outer portion of the plate and with an anchor supported at opposite ends respectively by the plate and said projecting stamping.

55 5. A brake backing plate with a central axle opening and having secured about said opening an annular reinforcing stamping having a lateral extension embracing spacers between itself and the plate, and provided with a camshaft bearing extending through the plate and the spacers and the lateral extension.

60 6. A brake backing plate with a central axle opening and having secured about said opening an annular reinforcing stamping having a lateral extension embracing spacers between itself and the plate, and provided

with a camshaft rotatably mounted and extending through the plate and the spacers and the lateral extension.

7. A brake backing plate with a central axle opening and having secured about said opening an annular reinforcing stamping having a lateral extension spaced therefrom, brake-operating means supported at one point by the plate and at another point spaced from the first point by said extension, and a brake anchorage adjacent said means and similarly supported by said extension and said plate.

8. A brake anchorage comprising the following parts in order: a backing plate, spacers, a reinforcing stamping, a shouldered bushing having its head engaging the stamping and adapted to have a brake shoe pivoted thereon, a second bushing mounted in a supporting member and engaging the end of the shouldered bushing, and a bolt passing through the two bushings and through aligned openings in the stamping and spacers and backing plate.

9. A brake anchorage comprising the following parts: a backing plate, a reinforcing stamping, a bushing having one end engaging the stamping and adapted to have a brake shoe pivoted thereon, a second bushing mounted in a supporting member and engaging the opposite end of the first bushing, and a bolt passing through the two bushings and through aligned openings in the stamping and backing plate.

10. A brake having a backing plate, three posts carried by said plate and carrying an outboard part spaced from said plate and one of which posts is adapted to serve as a brake anchor, and a shoe pivoted on said anchor post and having a relatively large clearance opening through which another of said posts passes.

11. A brake having a backing plate, three posts carried by said plate and carrying an outboard part spaced from said plate and one of which posts is adapted to serve as a brake anchor, and a shoe pivoted on said anchor post.

12. A brake anchorage comprising the following parts: a backing plate, a reinforcing stamping, a bushing having one end engaging the stamping and adapted to have a brake shoe pivoted thereon, a second bushing mounted in a supporting member and engaging the opposite end of the first bushing, and a bolt passing through the two bushings and through aligned openings in the stamping and backing plate, one of said bushings being eccentric and providing for an adjustment of the anchorage.

13. An adjustable anchorage comprising a backing plate and an anchor pin carried thereby, a member serving to support the end of said pin opposite the plate, and an eccen-

tric bushing on the pin between the plate and said member.

14. An adjustable anchorage comprising a backing plate and an anchor pin carried there-
5 by, and an eccentric bushing sleeved on the pin.

15. A backing plate having reinforcing means, an eccentric bushing engaging the reinforced part of the plate, and a bolt passing
10 through the bushing and plate and rigidly holding the bushing to adapt it to serve as a brake anchor.

16. A backing plate having an eccentric bushing adjacent thereto, and a bolt passing
15 through the bushing and plate and rigidly holding the bushing to adapt it to serve as a brake anchor.

In testimony whereof, we have hereunto signed our names.
